UNITED STATES PATENT OFFICE.

GUSTAV TEICHNER AND PAUL ASKENASY, OF NUEREMBERG, GERMANY.

PROCESS FOR ELECTROLYTICALLY PRODUCING PERSULFATES.

No. 880,599.

Specification of Letters Patent.

Patented March 3, 1908.

Application filed February 12, 1906. Serial No. 300,652.

To all whom it may concern:

Be it known that GUSTAV TEICHNER and PAUL ASKENASY, have invented a Process for Electrolytically Producing Persulfates, of 5 which the following is a clear and true specification.

The present invention consists of a process for electrolytically producing persulfates, as hereinafter particularly set forth.

10 It is known, that the output of persulfate depends in the first place on the potential at the anode. The higher this potential is, the greater is the output of persulfate. By adding very small quantities of certain substances to the electrolyte, the anodic potential and consequently the output of persulfate can be considerably increased. In this respect the ions Fl , Cl , ClO_4 , Cr_2O_7 , etc. have proved to be particularly effective.

20 Now we have found that the advantageous effect of the above mentioned additions gradually disappears and that the anodic potential as well as the output in persulfate considerably diminishes, when the 25 electrolysis is of long duration. It was further demonstrated that this decrease is due to the formation of the so called Caro acid (mono persulfuric acid) in the electrolyte. It is known that the persulfates, when dissolved in strong sulfuric acid are gradually 30 converted into Caro acid and that the speed of conversion increases with the degree of acidity. Thus for instance, the amount of Caro acid contained in a saturated solution 35 of sodium bisulfate and persulfate at 15°C . will increase about 0.3% in 24 hours. With a solution to which is added 10% of sulfuric acid, this increase will rise, under otherwise similar circumstances to about 0.6% in 24 40 hours.

We have found by experiments that the Caro acid is destroyed at the anode, oxygen being developed. The acid thus operates as an anodic depolarizing agent, thus causing a 45 corresponding decrease in the outputs of the persulfate. While, for instance, in the electrolysis of a saturated solution of sodium bisulfate containing $\frac{1}{2}\%$ of perchlorate of sodium, the anodic oxidation amounts to about 50 70%, it immediately sinks to about 45% on adding 1% of Caro acid and down to about

30% on adding 1% more of this acid. This difficulty can be obviated by destroying the Caro acid in the same proportion as it is formed. For this purpose reducing substances are added to the electrolyte and since Caro acid at ordinary temperature is a much more powerful oxidizing agent than persulfuric acid it will consequently be the first to be destroyed by such reducing substances. 55 60

If a reducing medium is added to a persulfate solution containing Caro acid, in proportion to the amount of the latter contained in the solution, the Caro acid will be destroyed without any loss of the persulfuric acid. Various substances may be employed as reducing medium for the Caro acid. For the production of persulfate of sodium, sulfite or bisulfite of sodium, hydrochloric acid and common salt have proved to be the 65 most suitable. The latter substances have a particularly favorable effect, since they simultaneously increase the anodic potential and consequently favorably influence the oxidation. This is most effectively carried 70 out in the following manner:—The speed of formation of the Caro acid in an electrolyte of given concentration and acidity, is first determined once for all, and then in the course of electrolysis such quantities of the 75 reducing substance are added, as are necessary for the reduction of this acid. An excess of the reducing substance should be avoided in order to avoid the simultaneous destruction of a part of the persulfate. If, 80 in consequence of an interruption of the electrolysis the electrolyte should contain greater quantities of Caro acid, it may again be rendered fit for electrolysis by adding at once the calculated amount of the reducing 85 substance. As an example:—25 liters of a saturated solution of bisulfite of sodium with the addition of 125 gr. or $\frac{1}{2}\%$ of perchlorate of sodium, are electrolyzed by a current of 25 amp. at a temperature of 15°C . 95 Since the speed of formation of the Caro acid, under these circumstances is 0.3% in 24 hours, i. e. 3 gr. of Na_2SO_5 per hour, 4 cubic centimeters of hydrochloric acid of 40% were added to the electrolyte per hour. 100 At the commencement of the electrolysis the output of persulfate of sodium amounted to

68% and after eight days of uninterrupted electrolysis it was still 63%. The above process may of course be employed for the production of other persulfates in a corresponding manner.

5 We claim as our invention:—

A process for producing persulfates, which consists in subjecting the solutions of the corresponding sulfates to electrolytic action and 10 periodically adding thereto, during the elec-

trolysis reducing agents adapted to reduce the Caro-acid as it is formed.

In testimony whereof we affix our signatures in the presence of two witnesses.

GUSTAV TEICHNER.
PAUL ASKENASY.
